UNITED STATES PATENT OFFICE.

MICAJAH B. HARLOW, OF TEKOA, WASHINGTON.

PHOTOGRAPHER'S FORM AND PRINT HOLDER.

No. 904,064.

Specification of Letters Patent. Patented Nov. 17, 1908.

Application filed April 29, 1908. Serial No. 429,867.

To all whom it may concern:

Be it known that I, MICAJAH B. HARLOW, a citizen of the United States, residing at Tekoa, in the county of Whitman and State 5 of Washington, have invented certain new and useful Improvements in Photographers' Form and Print Holders, of which the following is a specification.

My invention relates to photographers' 10 print and form holders, and particularly to a clamping frame for holding the print and cutting form in adjusted position while the photographer cuts or trims the print.

One of the main objects of my invention is 15 to provide a simple, durable, and inexpensive device of the above character that will enable the photographer or operator to adjust the cutting form with relation to the print instantaneously and to any desired degree and hold the same in adjusted position 20 without the complicated clamping and fastening means now in use, thus greatly accelerating the rapidity with which prints may be cut.

25 Other objects, such as to permit the changing of the cutting forms, and the changing of the forms without changing the cutting back, will be obvious from the description hereinafter set forth.

30 In the accompanying drawings, forming part of this specification, Figure 1, is a perspective view of my form and print holder. Fig. 2, is a longitudinal section of the same in open position. Fig. 3, is a similar view 35 in closed position.

Referring to these drawings, A represents 40 a rectangular base frame having at one end an overhanging cleat or projection B. Engaging the under side of the cleat B is the cutting table C, which is preferably mounted on a fulcrum D pivoted in the longitudinal sides of the base frame A. This cutting table C is preferably scarfed off at one end on the under side as at c although, of course, by 45 a slight change in the construction of the overhanging cleat B, this would not be necessary. Engaging the opposite end of the cutting table is a spring E, secured to the frame A, for normally holding the device in

open position. Obviously, this spring could 50 be secured to the cutting table, if desired.

The cutting table may be covered with a sheet of soft metal F if desired, although if the device should be made of aluminum this, of course, would be unnecessary. 55

The operation of this device is as follows: The print G and form H after being placed in approximate position are laid upon the cutting table with their edges under the overhanging cleat B. There is then sufficient friction to prevent slipping yet not enough to prevent easy adjustment relative to each other. When in satisfactory position the cutting table is depressed with one hand against the resistance of the spring E 60 whereupon the print and form are held in rigid position and the print may be cut to the desired shape without danger of the parts slipping.

Having thus described my invention, what 70 I claim as new and desire to secure by Letters Patent, is—

1. An article of the character described, comprising a frame having an overhanging cleat, a fulcrum pivoted in said frame and a 75 cutting table mounted on said fulcrum and adapted to engage said cleat when depressed.

2. An article of the character described comprising a rectangular frame, an overhanging cleat at one end thereof, a pivoted 80 fulcrum on said frame, a cutting table mounted on said fulcrum and adapted to engage said cleat, and a spring for holding said table in raised position.

3. In combination with a print and form, 85 a clamping means for holding said print and form in adjusted position comprising a frame with an overhanging cleat, a fulcrumed cutting table adapted to engage said cleat and means for normally holding said 90 table out of engagement with said cleat.

In testimony whereof I affix my signature in presence of two witnesses.

MICAJAH B. HARLOW.
